UNITED STATES PATENT OFFICE

HARRY D. SEVISON, OF ELKHART, INDIANA, ASSIGNOR TO THE ADLAKE COMPANY, OF CHICAGO, ILLINOIS, A CORPORATION OF ILLINOIS

WINDOW CONSTRUCTION

Application filed February 8, 1932. Serial No. 591,542.

This invention relates to improvements in sliding sash window construction, and has for its object the provision of particularly efficient means for maintaining a close bearing contact of the sash with the outer window stop whereby to prevent rattling when open and to effect a sealing against the elements when closed.

The attainment of this object is of especially great importance in connection with the windows of vehicles such as railway cars and buses, but it is also desirable with windows in houses and other structures.

In order that the invention may be readily understood, a preferred construction is herein described as predicated upon the accompanying drawings, the novel features of the construction pointed out in the appended claims, it being of course understood that the invention is not to be taken as restricted to the particular embodiment illustrated and described.

In the drawings:

Fig. 1 is an inside elevation of a window in which the invention is embodied;

Fig. 2 is an elevation of one of the inner sash stops, viewed in the plane of the sash;

Figs. 3, 4, 5 and 6 are horizontal sections taken on the respective section lines indicated on Fig. 2;

Fig. 7 is a vertical section through the sash, taken on the line 7—7 of Fig. 1, showing the sash in its closed position;

Fig. 8 is a similar view, showing the sash in a released and partially raised position;

Fig. 9 is a similar view, showing the sash in one of its stationary elevated positions.

The window shown in the drawings is provided, at each side thereof, with an outer stop 10 and an inner stop 11. Both stops are attached to the usual post plate 12 and are spaced apart from each other far enough to permit the sash 13 to slide freely up and down therebetween. To insure proper spacing, the inner stop 11 is provided with a flange 14 which projects outwardly therefrom along the face of the post plate into engagement with the base of the outer stop 10.

The inner stop 11, which preferably contains a curtain guide groove 15, is detachably

secured to the post plate by screws 16 or other suitable attaching means. This stop is of hollow sheet metal construction and contains a U-shaped reinforcing strip 17. The side of the inner stop which faces the sash is open, and the resulting channel 18 houses a lock rack 19.

The lock rack 19 differs from the ordinary lock rack in that it is vertically shiftable in the channel 18, for a purpose which will hereinafter be explained. The rack is reinforced by a backing strip 20 which extends from the lower end of the rack to a point short of the upper end thereof. In the vertical movement of the rack, the strip 20 bears against the base of the channel 18. Above the strip 20 the rack is preferably reduced in cross-section for a short distance, whereby to render the upper portion of the rack somewhat flexible with respect to the lower reinforced portion thereof. The rack is provided at intervals throughout the intermediate and lower portions thereof with inclined seats 21 for coaction with a pawl 22 which forms a part of the lock on the sash.

A shoe 23 is mounted on the upper end of the rack 19 for engagement with the upper portion of the sash. Behind the shoe the rack is provided with a cam block 24 which has an inclined face 25 for camming coaction with a cross pin 26 in the upper end of the channel 18. Another cross pin 27 is located in the upper end of the channel 18 for limiting the extent to which the shoe 23 can project from the channel. When the rack 19 is shifted downwardly, the block 24 will cam against the pin 26 and force the shoe 23 outwardly against the upper portion of the sash, thereby causing that portion of the sash to be pressed firmly against the outer stop 10.

A dog 28 is pivoted at 29 to the lower end of the rack and extends downwardly therefrom within the channel 18. The dog 28 is also pivoted at 30 to the inner stop 11, the pivot pin used being removably positioned in apertures in the sides of the channel whereby to facilitate assembling of the rack within the inner stop. The pivot points 29 and 30 are located at about the same level, with the result that any movement of the lower

end of the dog 28 farther into the channel 18 will cause the rack to be drawn downwardly in the channel and the shoe 23 to be forced against the upper portion of the sash.

5 The dog 28 is adapted to be engaged by the pawl 22 when the sash is closed. While the pawl 22 may be the nose of an ordinary throw-over type lock, it is shown herein as a pivotally mounted member which is cammed outwardly away from the sash by the beveled end of a bolt 31 when the bolt is projected into engagement therewith by a spring 32. A finger piece 33 is connected with the bolt 31 in such a way as to retract the bolt and allow the 15 pawl to return toward the sash when the finger piece is depressed. The particular lock assembly shown forms the subject matter of an application of Walter E. Keller, Serial No. 591,530, filed on even date herewith, 20 which application contains a detailed description of the lock structure.

When the sash is raised and the finger pieces 33 of the locks at both sides are released, the pawls 22 will be forced to assume 25 inclined positions in engagement with the racks 19 and will, upon being lowered into abutment with the nearest seats 21, shift the racks downwardly in the channels 18 under the weight of the sash. As a result of this 30 action, the shoes 23 will force the upper portions of the sash against the outer stops 10, and the throw-over effect caused by the inclined positions of the pawls and the weight of the sash, combined with the spring force 35 tending to move the pawls away from the sash, will force the lower portions of the sash against the outer stops, producing a tight, unyielding, noiseless, weather-proof engagement therebetween. The sash is shown in this 40 condition in Fig. 9.

To lower the sash from an elevated position, it is merely necessary to depress the finger pieces 33 and give the sash a slight upward movement, whereupon the pawls 22 will 45 drop back into the plane of the sash and the shoes 23 will be released, allowing the sash to be moved freely and to be lowered without any resistance into its closed position. The sash is shown in a freed condition in Fig. 8.

50 When the sash reaches its fully closed position, with the sealing strip 34 on the bottom rail of the sash in snug contact with the sill 35 of the window frame, releasing the finger pieces 33 will allow the lower ends of the pawls 22 to be forced away from the sash into engagement with the lower ends of the dogs and will cause the dogs to be deflected, thereby pulling down the racks 19, projecting the shoes 23 against the upper portions of 55 the sash, and pressing such upper portions against the outer stops. The reaction of the spring-derived force which moves the pawls 22 outwardly serves to press the lower portions of the sash tightly against the outer 60 stops, thereby producing throughout the en-

tire height of the sash a tight fit of the latter against the outer stops. This condition of the sash is shown in Fig. 7. The angle at which the bolts 31 bear against the pawls 22 when the latter are projected is preferably 70 such as to provide a substantial pressure of the pawls against the dogs 28. The angle also is preferably such as to prevent the pawls from backing up the bolts under strong wind pressures against the outside of the sash. 75

To open the sash, it is merely necessary to depress the finger pieces 33, whereupon the pawls 22 will drop back away from the dogs 28, the pressure applied by the shoes 23 will be released, and the sash will be freed in its 80 guides and can be raised without appreciable effort.

To prevent the sash from being opened from the outside, the lower ends of the pawls 22 may be provided with small shoulders 36 85 which extend under similar shoulders 37 on the lower ends of the dogs 28 and interlock vertically with the same.

The sill 35 of the window frame may be advantageously provided with a thin strip 38 of 90 unpainted brass or other suitable material for engagement with the sealing strip 34 to prevent the sticking which so frequently occurs when a rubber sealing strip is allowed to rest for any length of time on a painted portion 95 of a car window sill. The strip 38 is provided with a portion 39 which extends back under, and is securely clamped in position by, the usual sill cap 40.

100 I claim:

1. In window construction, the combination with a window frame having outer sash stops, and a vertically movable sash in the frame having normally projected lock members, of means actuated by the weight of the sash when the latter is raised and by the projection of the lock members when the sash is lowered for pressing the sash against the stops. 105

2. In window construction, the combination with a window frame having outer sash stops, and a vertically movable sash in the frame having lock-operating springs, of means actuated by the weight of the sash when the latter is raised and by the force of the springs when the sash is lowered for pressing the sash against the stops. 110

3. In window construction, the combination with a window frame having outer sash stops, and a vertically movable sash in the frame having lock-operating springs, of means actuated by the weight of the sash when the latter is raised and by the force of the springs when the sash is lowered for pressing the sash against the stops, said means including a vertically shiftable lock rack at 120 each side of the frame for supporting the sash at any one of several predetermined elevations, a shoe at the upper end of the rack 125 which is cammed toward the sash when the 130

rack is shifted downwardly, and a member at the lower end of the rack which is actuated by the action of the lock-operating spring at that side of the shoe to shift the rack downwardly.

4. In window construction, the combination with a window frame having outer sash stops, and a vertically movable sash in the frame having normally projected lock members, of means actuated by the weight of the sash when the latter is raised for pressing the sash against the stops, said means including a vertically shiftable lock rack at each side of the frame for supporting the sash at any one of several predetermined elevations, a shoe at the upper end of the rack which is cammed toward the sash when the weight of the sash on the rack shifts the latter downwardly, and a connection between the shoe and the sash-supporting portion of the rack which permits the shoe to be cammed toward the sash without a corresponding movement of the sash-supporting portion of the rack toward the sash.

25 5. In window construction, the combination with a window frame, and a vertically movable sash in the frame, of outer sash stops, inner sash stops having channels which open toward the sash, movable lock racks in the channels, shoes connected with the upper ends of the racks for engagement with the sash, and means for causing the weight of the sash when raised to move the racks in such a way as to force the shoes against the sash.

6. In window construction, the combination with a window frame, and a vertically movable sash in the frame, of outer sash stops, sheet metal inner sash stops formed with channels which open toward the sash, movable lock racks supported by the sides of the channels within the latter, and means for causing the sash to be pressed against the outer stops when the lock racks are moved.

45 7. In window construction, the combination with a window frame, and a vertically movable sash in the frame, of outer sash stops, inner sash stops, vertically shiftable lock racks associated with the inner stops, shoes which are mounted on the upper ends of the racks, means for moving the shoes toward the sash when the racks are shifted downwardly, and dogs which are pivotally connected to the racks and are also pivotally connected to the inner stops for shifting the racks downwardly when the dogs are oscillated.

In testimony whereof I have hereunto subscribed my name.

HARRY D. SEVISON.
